UNITED STATES PATENT OFFICE

2,253,468

PORTABLE GRAVELING EQUIPMENT

Leslie A. Layne, Houston, Tex., assignor to The Texas Company, a corporation of Delaware

Application May 31, 1938, Serial No. 210,967

1 Claim. (Cl. 302—14)

The invention relates to a portable graveling equipment which is particularly adapted for the introduction of gravel or similar materials into well bores by means of the circulation of a carrier liquid.

The present application refers to my prior co-pending applications 729,025 and 729,026, both filed on June 4, 1934, which applications are in turn continuations in part of the parent application, Serial No. 556,343, filed August 11, 1931 which parent application has resulted in Patent No. 1,975,162 dated October 2, 1934.

It is one of the objects of the invention to provide a truck capable of circulating liquid and gravel into a well bore under pressure in order to provide a gravel filter in the well.

Another object of the invention is to provide a portable graveling device which is self-contained in that all of the equipment necessary to hoist and transfer the gravel under pressure is arranged in a unitary assembly.

Still another object of the invention is to provide an arrangement of gravel drums wherein one drum can be filled and subjected to pressure ready to discharge its gravel while the alternate drum is being discharged.

Still another object of the invention is to provide an arrangement of gravel drums and piping connections therefor so that carrier liquid may be introduced and discharged from the gravel drums and the circulation of liquid so controlled that any desired volume of gravel may be carried along with the liquid.

Other and further objects of the invention will be readily apparent when the following description is considered in connection with the accompanying drawings, wherein:

Fig. 1 is a side elevation of the truck in position ready to conduct the graveling operations.

Fig. 2 is a broken detailed view looking at the piping and valve controls on the forward side of the gravel drums.

Fig. 3 is a vertical sectional view taken on the line 3—3 of Fig. 2 and showing a sectional view of the inlet and discharge of the gravel drum.

Fig. 4 is a sectional view showing the closure mechanism at the top of the drum.

In Fig. 1, the truck is illustrated generally at 2 and may be of any desired type, size or style so long as it is arranged with a power take-off 3 for driving the sprocket wheel 4.

The sprocket 4 drives the chain 5 and through a train of gears rotates the drive wheel 6 of the pump 7. The pump 7 may be of any desired type,

but is here shown as a reciprocating pump by which a flow of liquid is discharged into the pipe 8. The suction pipe 9 draws liquid from a suitable source.

Fig. 2 shows an enlarged view of the parts in the rear of the truck and the pipe 8 is illustrated upon the floor 12 of the truck.

The pipe 8 extends rearwardly and is then turned upward at 14 and has the flexible hose 15 connected therewith and through which hose either liquid or gravel and liquid may be discharged into the well bore which is not shown.

A direct flow of liquid may be circulated from the pump through the pipes 8 and 15 by opening the valves 16 and 17 on the pipes 8 and 14 respectively, or if desired a flow of liquid under pressure may be supplied through the branch 18 on the pipe 8 from any source of pressure if the pump 7 is not to be used. Both sources may be used if desired.

In operation, assuming that the drum 20 is filled with gravel as will hereinafter be explained, it is usual to wash the well by circulating liquid through the pipe 15. During this operation the valve 17 will be wide open and if the liquid is coming from the pump 7 the valve 16 will be open. It is now desired to apply pressure to the drum 20 and the valve 19 in the pipe 23 will be opened wide. The valve 32 in the discharge pipe 30 will also be fully opened. In this manner the same pressure that is in the pipes 14 and 15 will be applied to the drum. In order, however, to force some of the liquid through the drum 20 the control valve 17 will now be partly closed. Any restriction in the valve 17 will cause the liquid to be by-passed from the pipe 14 through pipe 23 and through the drum 20 back through pipe 30 into the pipe 15 beyond the valve 17. Thus by manipulation of a single valve the operator can control the percentage of flow which will be passed through the drum and consequently the rate of flow at which the gravel will be picked up and discharged from the drum into the well. By opening the valves 19 and 32 fully, it is only necessary to manipulate the one valve 17 to obtain a very accurate and delicate control.

The application of pressure to the drum 20 will be available against the closure 27 so as to force it into sealing position with the top of the drum so that the applied pressure will be used to discharge the gravel. The carrier liquid from the inlet pipe 23 enters the drum 20 near the base 24 thereof as best seen in Fig. 3.

The discharge of the carrier liquid into the

gravel 25 in the drum 20 will cause an agitation of the gravel so that it is suspended in spaced relation in the carrier liquid as indicated in the lower portion 26 of the drum by the spaced apart relationship of the particles of gravel.

The discharge pipe 30 extends upwardly and merges at 31 with the pipe 15 beyond the valve 17. This pipe 30 carries the discharge valve 32. With a little experience the operator is able to judge the volume of gravel being discharged by the tone or sound of the gravel passing through the pipe 15.

It is this regulation of the carrier liquid, its pressure and volume that accomplishes a satisfactory operation of this equipment in carrying the gravel in spaced relationship in the carrier liquid.

The closure for the top of the drum is best seen in Fig. 4 and includes the closure member 27 which is pivoted upon a lever member 40 which is in turn pivoted on the flange 42. This flange is fastened to the top 43 of the drum by a plurality of bolts 44. A slot 45 in the flange 42 permits pivoting of the lever 40 and if desired a catch 46 may be arranged to engage a hook 47 on the top of the drum so that the closure 27 may be latched in closed position to hold it temporarily in place until pressure is applied to the drum so as to move the edge 48 of the closure into engagement with the seal 49 on the flange 42.

The piping and valves as applied to the drum 21 on the left hand side of Fig. 2 are the same as just described for the drum 20 and it seems obvious that by manipulation of first one drum and then the other that they may be alternately used so that one drum may be discharging through the hose 15 into the well while the other drum is open, the pressure released and the gravel being introduced. Attention is directed to the fact that the control valves are positioned at an elevation above the gravel drums so that they will not become clogged.

It is of course desirable to hoist the gravel so that it may be introduced into the drums and to accomplish this a hopper 50 has been shown in Fig. 1 as arranged to be lowered to the ground so that it may be readily filled with gravel. The frame 51 is shown in Fig. 1 as having an inclined portion 52 so that wheel barrows may be used to convey the gravel into the hopper.

A bail 53 on the hopper has a cable 54 connected therewith by which the hopper is raised and lowered. A davit 56 is carried upon a trunnion 57 on the back end of the truck between the gravel drums and this davit carries suitable

pulleys so as to guide the cable 54 to a suitable block and tackle arrangement, not shown.

The support 57 upon which the davit 56 is mounted may be folded backwardly so that it extends over the truck and reduces the overall height of the apparatus. The davit 56 is arranged to turn about the vertical axis in the support 57 and can be moved by a handle 67 which extends from the davit.

In this manner after the hopper is hoisted it may be turned to either side so that the tapered lower portion 68 thereof may be lowered into the tapered flange 42 to insure deposit of the gravel into the drum.

When the gravel is exhausted from one of the drums, of course the drum will be filled with liquid and when a new deposit of gravel is introduced into the drum the liquid will be displaced and an outlet pipe 70 has been shown extending from the top 43 of the drum as best seen in Fig. 2. A quick opening valve 72 is provided on this outlet because as the gravel drops from the hopper into the drum there will be a large volume of water displaced. This outlet 70 is directed downwardly and terminates at 73 to direct the liquid on the ground.

If desired, a support or screw jack 75 may be hinged at 76 on the base of the drum so that it may be moved around to a vertical position and extended so as to support the load of liquid and gravel carried by the drums during the graveling operation. Brackets 77 normally hold the jack in the position seen in Fig. 1.

Broadly, the invention contemplates a simple and economical portable graveling equipment which is arranged to speedily introduce a flow of liquid and gravel into a well bore under pressure.

What is claimed is:

In a surface equipment for well graveling including a pair of spaced drums, a pump to circulate liquid, a pipe to receive such liquid, a valve in said pipe, a branch pipe from a point in said first pipe at the upstream side of said valve and leading to each of said drums, a valve in each branch pipe to control the flow therethrough, a discharge pipe from each drum to said first pipe beyond said first valve, and valve means in each discharge pipe, said pipe, piping and valves being so constructed and arranged that liquid may be circulated past said drums, into and out of either or both drums, and directed partly through either drum and partly through the pipe in order to control the rate of discharge of gravel from said drums.

LESLIE A. LAYNE.
